UNITED STATES PATENT OFFICE.

LOUIS A. SCHOLZ, OF ROANOKE, VIRGINIA.

FRUIT-JAR.

1,140,486.

Specification of Letters Patent. Patented May 25, 1915.

Application filed August 19, 1913. Serial No. 785,495.

To all whom it may concern:

Be it known that I, LOUIS A. SCHOLZ, a citizen of the United States, residing at Roanoke, in the county of Roanoke and State of Virginia, have invented certain new and useful Improvements in Fruit-Jars, of which the following is a specification.

My invention relates to an improvement in fruit-jars, the object being to provide an air-tight and sanitary seal which will insure the preservation of the contents of the jar.

With this object in view, my invention consists in a fruit-jar having a groove formed at the top adapted to receive paraffin or like material, and a lid having a ring or flange adapted to enter this groove and to be held away from the bottom thereof, so that a film of paraffin shall intervene between the groove and ring or flange at all times, being sides occupying the space between the upper edge of the groove and the ring or flange, which latter is of sufficient size to accommodate the surplus paraffin, thus insuring an air-tight joint.

In the accompanying drawings:—Figure 1 is a vertical section; Fig. 2 is a bottom plan view of the lid; and Fig. 3 is a view of a prepared paraffin ring adapted to fit the mouth of the jar.

The jar 1 is of any approved construction, as for instance the Mason type of fruit-jar, made of glass of any size and shape, except that the glass at the mouth instead of being screw-threaded is enlarged and widened and provided with an annular groove 2. The outer edge of the mouth is preferably rounded as at 3, and in a slightly higher plane than the inner edge 4.

The lid 6 is made of solid glass and provided with a ring or flange 6^a, rounded and enlarged at its lower or outer edge 7 to correspond in shape with the groove. This enlarged edge extends inward, whereby to form a space 8 between it and the inner edge 4 of the mouth to receive the surplus paraffin. This flange or ring is provided with transverse notches 9, 9, for the escape of air. A prepared ring of paraffin 10 is inserted in the groove. The heat from the jar in canning melts the paraffin, the lid is then placed on with the flange or ring in the groove, and the outer edge resting upon the rounded edge 3 of the mouth, thus hold-

ing the ring or flange slightly away from the bottom of the groove, as shown in Fig. 1, 55 and the lid from the inner edge 4 of the mouth. The purpose of this is to provide the space for a film of the paraffin or wax to completely surround the flange or ring, and any surplus to find and fill the space 8 between the inner edge 4 of the mouth and the flange or ring. By leaving this space at least one-sixteenth inch (1/16'') for the paraffin, it not only makes an air-tight joint, but also affords space for contraction and 65 expansion.

When the lid is on, it is held by any of the well-known forms of wire or tin clamps to hold the lid in place and prevent its being disturbed during handling. After filling 70 and securing the lid in place, the jar is allowed to cool, and, as the material contracts, an absolutely air-tight joint is formed.

By this form of fruit-jar, I have provided a much more sanitary and hygienic jar than 75 heretofore, which at the same time eliminates the most important objections to the old-fashioned fruit-jar having the screw-top and gasket now on the market.

Having fully described my invention, 80 what I claim as new and desire to secure by Letters Patent, is:—

The combination with a fruit jar having an annular groove at the mouth so formed that an inner and outer rim are provided, 85 the inner rim to be of less height than the outer rim, of a lid having a ring on the lower side, the ring made to be of less transverse extent than the groove for forming a continuous channel beneath the ring, and said 90 ring of such a diameter that when fitted to the groove a greater channel is left on the inside of the ring than on the outside, an enlargement provided on the lower inner edge of the ring, and said lip adapted, when 95 in place, to rest on the outer rim of the jar so that as a sealing medium is placed in the groove and the lid is fitted to the jar, the sealing medium will close up around the ring and over the enlarged portion. 100

In testimony whereof I affix my signature, in the presence of two witnesses.

LOUIS A. SCHOLZ.
